UNITED STATES PATENT OFFICE.

JOHN HAYS HAMMOND, JR., OF GLOUCESTER, MASSACHUSETTS.

SYSTEM OF ETHER-WAVE CONTROL.

1,339,927.

Specification of Letters Patent. Patented May 11, 1920.

Application filed December 27, 1910, Serial No. 599,625. Renewed September 29, 1919. Serial No. 327,868.

To all whom it may concern:

Be it known that I, JOHN HAYS HAMMOND, Jr., a citizen of the United States, residing at Gloucester, in the State of Massachusetts, have invented certain new and useful Improvements in Systems of Ether-Wave Control, of which the following is a specification, reference being had to the accompanying drawings, forming a part hereof.

The invention relates broadly to means for transmitting signals or messages by wireless waves or impulses.

One of the objects of the invention is to provide a sending station at which the intensity of the emitted waves or impulses may be modified by sound waves. A further object of the invention is to provide wave receiving means at the receiving station which will be responsive to variations in the intensity of the impulses emitted from the sending station and in which the sound waves will be reproduced. The various other objects of the invention will be more fully set forth in the following description of one form of mechanism embodying my invention which consists in the new and novel features hereinafter set forth and claimed.

In the accompanying drawings—

Figure 1 is a diagrammatic view of a sending station embodying my improvements.

Fig. 2 is a diagrammatic view of a receiving station embodying my invention.

Fig. 3 is a diagrammatic view of a modified arrangement of a receiving station.

Referring now to the drawings, Fig. 1 designates a sending station at which is located a suitable source of energy 1. This source 1 is included in a "primary" circuit which comprises, in series also, a microphone 2 suitable for use with high tension currents, a non-inductive resistance 3, an inductance 4 and an arc 5. In a circuit shunted across the arc 5 is a suitable condenser 6 and the primary 7 of a transformer whose secondary 8 is connected with the aerial 9, whereby rapidly oscillating undamped waves may be emitted.

The receiving station is likewise provided with a suitable aerial 10, and with a coil 11 which is connected in series with a rectifying detector 12. Shunted across said detector is a telephone receiver 14 and a vibrating relay

15, adapted to be cut in or out of circuit by means of a suitable switch 16. A local circuit including a suitable source of energy as the battery 17 is normally closed through a suitable contact device 18 such as a platinum point attached to the diaphragm of said vibrating relay. In this circuit is included, furthermore, a relay 19, such as the well-known Morse relay, in circuit with the battery 17, and a condenser 20 is shunted across said circuit. The relay 19, has its armature 21 normally attracted, and controls a normally open second local or operating circuit, comprising a suitable source of energy as the battery 22 and also suitable apparatus 23 responsive to the current flowing in the operating circuit when the same is closed upon the release of the armature 21 of the relay 19. The apparatus 23 is shown as an electric alarm bell for the sake of simplicity; but it is understood that other electrically controlled apparatus may be substituted for the said bell 23, and may be in turn employed to control or operate other electrical or mechanical apparatus.

Fig. 3 designates another form of receiving station, embodying a different kind of vibrating relay and contact device. In this construction the vibrating relay 15 is replaced by a similar device 24, which differs from that first described in that it has attached to its diaphragm a rod 25 of any suitable material. The end of this rod projects into the spout 26 of a mercury reservoir 27 in such a manner as to leave the spout normally open and to close the passage and to interrupt the flow of mercury through the spout only when the diaphragm of the relay 24 and the rod 25 vibrates. The falling stream of mercury 28 impinges against a metal plate 29, and then flows into a receptacle 30 from which it is pumped back into the mercury reservoir 27 by a pump 31. The terminals of a local circuit are respectively connected to the mercury in the mercury reservoir 27 and to the metal plate 29. This local circuit includes also a suitable source of energy 17, a condenser 20 in shunt circuit, and a relay 19, the armature 21 of which, when released, closes a second normally open local circuit and actuates a bell 23 or other suitable device, as before described.

The operation of my system is as follows: When the human voice or other sound

2
producing means actuates the diaphragm of the microphone 2, located at the sending station, there will be a corresponding change in certain characteristics of the oscillatory waves propagated from the aerial of the sending station. These oscillatory waves are received by the aerial 10 of the receiving station. So long as the microphone 2 is at rest the train of waves emitted from the aerial 9 will be of a constant and undamped character; and, because of their high frequency of oscillation, the currents induced by them pass through the rectifying detector 12 in a series of rapid impulses of uniform direction and intensity.

Owing to the inertia of the diaphragms of the telephone receivers 14 and the relays 15 and 24, these extremely rapid impulses of rectified current do not cause any appreciable vibration of the diaphragms, and consequently no sound will be heard in the telephone receivers 14. While the effect of these extremely rapid and weak impulses upon the diaphragms of the relays 15 and 24 may be substantially the same as that which would be produced by a practically steady but slight pull upon these diaphragms, this effect is not sufficient to open the contact device 18 of the relay 15 of Fig. 2, and has no tendency to close the spout 26 of Fig. 3. But when the diaphragm of the microphone 2 is actuated by sound waves, such for instance as by the sound waves of the human voice, variations in accordance with the sound waves are produced in the amplitude or intensity of the oscillations transmitted by the sending station and these cause corresponding variations in the amplitude or intensity of the resultant impulses which act upon the diaphragms of the receiving station and consequently these diaphragms are vibrated in accordance with the sound waves thus transmitted from the sending station and corresponding sounds may be heard in the receiving telephones 14. This vibration of the diaphragm of the relay 15 of the system shown in Fig. 2 causes a rapid and repeated opening and closing of the contact device 18 and a corresponding rapid and repeated opening and closing of the circuit through the battery 17 which causes the release of the armature 21 of the relay 19 and a consequent closing of the circuit through the battery 22 and electric bell 23 or other device.

When the receiving system shown in Fig. 3 is used in connection with the transmission system shown in Fig. 1, the operation is similar to that just described in connection with Fig. 2. When the microphone 2 is at rest, the diaphragm of the relay 24 is acted upon as hereinbefore described, by a series of rapid weak impulses of uniform direction, but on account of the weakness

and high frequency of these impulses and the inertia of the diaphragm, the diaphragm is practically unaffected and is permitted to remain in such a position as to leave the outlet through the spout 26 normally open, 70 thus permitting a steady stream of mercury to flow downwardly through the spout and to impinge against the inclined metal plate 29, thus maintaining the circuit through the battery 17 normally closed. 75 But when the microphone 2 is acted upon by sound waves, the amplitude or intensity of the electroradiant oscillations emitted by the aerial 9 is varied in accordance with the sound waves and the amplitude of the 80 impulses received and acting upon the diaphragm of the relay 24 of the receiving station is accordingly varied and thus causes the diaphragm to vibrate and to vibrate the rod 25 which then alternately closes and 85 opens the passage through the spout 26 of the mercury reservoir, and alternately closes and opens the passage through the spout. The stream of mercury 28, which normally flows without interruption, is thus 90 broken into a series of drops by the vibrations of the rod 26. The result is that the first local circuit is broken, with the result that the second local circuit 95 is closed and the bell 23 or other mechanism is operated, as before described.

It will be understood that many changes and modifications within the knowledge of those skilled in the art may be made in the application of the system and improvements 100 herein disclosed. It is obvious of course that any other form of electrically controlled mechanism may be substituted for the said electric bell, and that by employing suitable apparatus any number of mechanical movements may be controlled as desired, through the agency of sound-waves and at any desired distance from the sending station. 105

I claim as my invention:

1. The combination with a container provided with an outlet and adapted to hold a conducting liquid, of vibratory means arranged to control said outlet, and operative to open and close said outlet in accordance with variations in electrical oscillations, said 110 variations corresponding to sound waves, a conductive terminal spaced below said outlet and in vertical alinement therewith and arranged to receive liquid flowing from said outlet, a receptacle extending beneath said terminal and arranged to receive the liquid flowing therefrom, a terminal projecting into said container, an electric circuit connecting said terminals, and means for withdrawing liquid from said receptacle and delivering the same into said container. 115

2. The combination with a transmitting station for continuously emitting waves of constant amplitude and high frequency, and a device for increasing the amplitude of 120 125 130

certain waves at will, of a receiving station including a local circuit, circuit controlling means therefor including a receptacle arranged to deliver a stream of conducting liquid, said controlling means being unresponsive to currents set up by said waves of constant amplitude but responsive to currents set up by said waves of increased am-

plitude, and signaling mechanism controlled by said circuit.

This specification signed and witnessed ¹⁰
this 23rd day of November, A. D. 1910.

JOHN HAYS HAMMOND, JR.
